US0D1004728S

(12) **United States Design Patent** (10) **Patent No.:** **US D1,004,728 S**
Hunter (45) **Date of Patent:** **** Nov. 14, 2023**

(54) **WATER RIDE**(71) Applicant: **ProSlide Technology Inc.**, Ottawa (CA)(72) Inventor: **Richard D. Hunter**, Ottawa (CA)(73) Assignee: **ProSlide Technology Inc.**, Ottawa (CA)(**) Term: **15 Years**(21) Appl. No.: **29/821,850**(22) Filed: **Jan. 4, 2022****Related U.S. Application Data**

(62) Division of application No. 29/711,440, filed on Oct. 31, 2019, now Pat. No. Des. 943,043.

(30) **Foreign Application Priority Data**

May 24, 2019 (CA) ..... CA 187680

(51) **LOC (14) Cl.** ..... **21-03**(52) **U.S. Cl.**USPC ..... **D21/819**(58) **Field of Classification Search**

USPC D21/811, 814, 818-821

CPC A63G 21/00-21/22

See application file for complete search history.
